WILLIAM F. KEENAN, OF NEWARK, NEW JERSEY, ASSIGNOR TO GEORGE J. LOWRES, OF NEWARK, NEW JERSEY.

TENSION-SPRING FOR EYEGLASS-MOUNTINGS.

1,177,868.

Specification of Letters Patent.

Patented Apr. 4, 1916.

Application filed January 16, 1914. Serial No. 812,381.

To all whom it may concern:

Be it known that I, WILLIAM F. KEENAN, a citizen of the United States, residing at Newark, in the county of Essex and State of New Jersey, have invented certain new and useful Improvements in Tension-Springs for Eyeglass-Mountings; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in tension-springs for eyeglass mountings; and, the invention has reference, more particularly, to a novel construction of spring for placing under tension the nose-guards of an eye-glass mounting and the manipulating finger-pieces connected with said nose-guards.

The present invention has for its principal object to provide a novel construction of flat spiral spring provided with a novel means for easily and quickly adjusting the spring in its relation to the eye-glass mounting and the nose-guards, without removing the spring from its assembled relation with the parts of the eye-glass mounting and the nose-guards, whereby the tension or spring-pressure upon the nose-guards may be regulated and adjusted to the desired degree, and thereby assure a proper and comfortable fit and pressure of the nose-guards upon the nose of the wearer of the eye-glasses.

Other objects of this invention, not at this time more particularly enumerated, will be clearly understood from the following detailed description of the invention.

With the various objects in view, the said invention consists, primarily, in the novel tension-spring hereinafter set forth; and, this invention consists furthermore, in the novel arrangements and combinations of the several parts of the spring, all of which will be more fully described in the following specification and then finally embodied in the clauses of the claim which are appended to and which form an essential part of this specification.

The invention is clearly illustrated in the accompanying drawings, in which:

Figure 1 is a detail perspective view of a

portion of an eye-glass mounting having a nose-guard pivotally connected therewith, said view illustrating also in connection therewith a tension-spring made according to and showing one embodiment of the principles of the present invention. Fig. 2 is a top or plan view of the tension-spring detached from the eye-glass mounting, said view being drawn on an enlarged scale; Fig. 3 is a side elevation of the tension-spring; and Fig. 4 is a vertical cross section of the same, said section being taken on line 4—4 in said Fig. 2.

Similar characters of reference are employed in all of the hereinabove described views to indicate corresponding parts.

Referring now to the said drawings, the reference-character 1 indicates the bridge-piece of an eye-glass mounting, the same terminating in the lens-embracing members 2, in which one of the lenses 3 of the eyeglasses is secured. The end of the bridge-piece 1, adjacent to the lens-embracing members 2, is flattened out slightly to provide a supporting table or base 4 from which projects, vertically, a post 5, preferably in the form of a screw. Pivottally mounted upon said post 5 is a lever-arm 6, one end of which terminates in a suitable nose-guard or gripping element 7, and the other opposite end of said arm terminating in a suitable finger-piece 8 for oscillating said lever arm and the nose-guard connected therewith, to spread-apart the oppositely facing nose-guards of the complete eye-glass mounting for the purpose of adjusting the same to the nose of the wearer, as will be understood, and all of which is old and well known to those familiar with the construction and manufacture of eye-glass mountings.

The reference-character 9 indicates the complete novel adjustable tension-spring made according to and embodying the principles of the present invention, the same comprising a main spiral spring-body 10, the same being preferably flat in form, or in the form of a thin band or ribbon, and the convolutions of which lie one within another and in the same plane. Extending outwardly from the outer end of said main spiral spring-body 10 is an anchor-arm 11, the free end of which is formed into a U-shaped or other suitably-shaped receiving-portion as 12. Connected integrally with the inner end of said main spiral

spring-body 10 is a helical-portion 13, the same providing a helix ascending above the plane of the main spiral spring-body 10, so as to be positioned above the said body, 5 substantially in the manner illustrated. The said helical portion 13 is preferably circular in cross section, and terminates in an outwardly extending anchor-arm 14. The said novel adjustable tension-spring, thus constructed, is mounted upon the said post 10 5 of the eye-glass mounting, so as to extend around the same, and is preferably arranged so as to lie above the said lever-arm 6 pivoted upon said post 15 5. The receiving portion 12 is then hooked over a portion of said lever arm 6, so that the latter is received therein. The anchor-arm 14, which extends outwardly from said helical portion 13, is now carried behind and bent around one of said lens-embracing 20 members 2 of the eye-glass mounting, this operation placing the tension-spring under tension, so that it presses the lever-arm forwardly and thereby carries the nose-guard 25 7 into gripping relation with the nose of the wearer, the nose-guards being released from such relation by manipulating the finger-piece 8, so as to swing said lever-arm 6 in the opposite direction and against the tension of said tension spring. If the said tension spring, when thus mounted, does not provide enough tension or pressure upon the lever-arm 6, to firmly hold the nose-guard in its gripping relation with the nose, the tension 30 35 of the spring may be easily increased, without in any way disturbing the assembled relation of the same with the eye-glass mounting and its parts, by grasping the end of said anchor-arm 14 and pulling the same in an outward direction, without removing it from its engagement with the lens-embracing member 2. This operation causes a contraction or tightening-up of the said helical-portion 13 of the spring, which contraction or tightening up effect is also transmitted by said helical-portion 13 to the inner end of the main spiral spring-body 10. Consequently, the said main spring-body is more tightly coiled, and thereby increasing the tension thereof, 40 45 which results in an increased actuating pressure upon the said lever-arm 6, and consequently upon the nose-guard 7, as will be clearly evident. If, however, said tension-spring is found to be too stiff; that is, to press too strongly upon the said lever-arm 6, so as to cause the nose-guard 7 to bind or grip too tightly upon the nose of the wearer, to the latter's discomfort, the 50 55 pressure thereof may be relieved, by moving or pushing the anchor-arm inwardly. This operation causes an expansion or loosening-up of the helical-portion 13 of the spring, which expanding or loosening up effect is 60 65 also transmitted by said helical-portion 13

to the inner end of the main spiral-body 10, consequently tending to move the said inner end of the latter in such a direction as to slightly loosen up the coils of said main spiral spring-body 10, and thereby reducing 70 the tension thereof, which results in decreasing the actuating pressure upon said lever-arm 6, and of the latter upon said nose-guard 7.

The important feature of the construction of my novel spring lies in providing the helical-portion 13 between the anchor-arm 14 and the inner end of the main spiral spring-body 10, since any movement of said anchor-arm in or out, which is a movement 80 or force applied and directed in a straight line is when transmitted to said helical portion converted thereby into a force operating along the line of its spiral. Consequently, when that force reaches the inner 85 end of said main spiral spring-body 10, it does not tend merely to push one convolution of said spiral spring-body 10 against another, with little or no expanding or contracting effect upon said convolutions; but, 90 being applied to the inner end of said main spiral spring-body 10, along lines corresponding to the direction or line of its spiral formation, a full and complete expanding or contracting effect may be secured to the most delicate degree. 95

It will, therefore, be apparent that my novel construction of tension-spring may be so manipulated as to easily and quickly adjust its tension to any desired degree, 100 without disturbing its assembled association with the eye-glass mounting and the parts thereof; and, consequently, a wide and delicate range of adjustment and regulation of the pressure of the nose-guards of 105 the eye-glass mounting, as actuated by said springs, may be secured, so that a perfect and comfortable fit of the eye-glasses to the wearer's nose is assured. 110

I claim:—

1. A nose-guard spring for eye-glass mountings comprising a spiral spring-body of flat or band-like form, the convolutions of which lie in the same plane, a helical portion of circular cross-section connected with the inner end of said spiral spring-body and ascending out of the plane of the latter, so as to lie above the same, and outwardly extending portions projecting respectively from the outer end of said spiral spring-body and from the outer end of said helical portion, substantially as and for the purposes set forth. 115 120 125

2. A nose-guard spring for eye-glass mountings comprising a spiral spring-body of flat or band-like form, the convolutions of which lie in the same plane, a helical portion of circular cross-section connected with the inner end of said spiral-body and ascending out of the plane of the latter, so as to lie 130

above the same, an anchor-arm extending outwardly from the outer end of said spiral spring-body having a receiving-portion at its free end, and an anchor-arm extending 5 outwardly from the outer end of said helical portion and adapted to be adjustably associated with a fixed point of anchorage.

Copies of this patent may be obtained for five cents each, by addressing the "Commissioner of Patents, Washington, D. C."

In testimony, that I claim the invention set forth above I have hereunto set my hand this 14th day of January, 1914.

WILLIAM F. KEENAN.
